UNITED STATES PATENT OFFICE.

JOHN JAMES, OF FORT ATKINSON, WISCONSIN, ASSIGNOR TO JAMES MANUFACTURING COMPANY, OF FORT ATKINSON, WISCONSIN, A CORPORATION OF WISCONSIN.

MEANS FOR SETTING UP ANCHORS.

1,199,077.

Specification of Letters Patent. Patented Sept. 26, 1916.

Application filed December 7, 1914. Serial No. 875,785.

To all whom it may concern:

Be it known that I, JOHN JAMES, a citizen of the United States, residing at Fort Atkinson, county of Jefferson, and State of 5 Wisconsin, have invented new and useful Improvements in Means for Setting Up Anchors, of which the following is a specification.

My invention relates to improvements 10 in means for setting up anchors in concrete work.

In erecting stables and similar structures having concrete floors, it is necessary that the concrete itself be prepared and 15 placed in the molds at the point of use, and this work is frequently done by the owner of the premises and his associates, who usually have had little experience in such work and therefore find great difficulty in 20 properly locating anchorage members to facilitate the attachment of posts, frames, and partitions to the concrete floor, and the fact that the anchors are embedded in the concrete, makes it impossible to change the 25 location of the anchorage elements after the concrete is set. Accordingly it has heretofore been the usual custom to employ experts skilled in the art of erecting concrete structures to direct the setting of the anchors in 30 the molds in accordance with a previously prepared plan. This has been done notwithstanding the fact that the cost of employing such experts, including their traveling expenses, etc., is great and tends to make 35 the total expense of erecting such structures prohibitive.

The object of my invention is to provide means, whereby skilled experts at a shop or factory, where both bold elements 40 and anchor members are constructed, may temporarily set up the mold element and anchor members in proper relation to each other and in accordance with the plan of a building to be erected at a distance, the 45 various elements, including the setting up members, the mold walls, and the anchors being adapted to be separated and shipped in compact knock-down form under conditions which substantially preclude the possibility of destruction or injury in transit, all 50 of the elements being so constructed that when reassembled in position for pouring the concrete, they are necessarily adjusted in the exact position which they occupied 55 when temporarily assembled at the shop.

Primarily, the invention contemplates the provision of means for accurately positioning the anchor with respect to the mold walls, such positioning means being detachably secured to the anchor and adjusted when 60 the anchor is placed in the mold and co-operating with the mold walls to hold the anchor at the desired position, the anchor and positioning means constituting a unit independently of the mold walls. 65

My invention contemplates the shipment of the setting up devices and the anchors to which they pertain, as separate units, the members of the mold, (ordinarily the side members only), being packed for shipment 70 in units which are independent of the other units, while being transported to the place of use.

The drawings illustrate my invention as applied to units to be used in constructing 75 a stable floor.

Figure 1 is a perspective view of one of the units with its elements assembled in knock-down form, and comprising a post anchor and a pair of setting up devices relating thereto. Fig. 2 is a perspective view of the same unit as it appears with its elements assembled in position for connection with the walls of a mold. Figs. 3 and 4 are similar views showing a stanchion supporting anchor in knock-down and setting up relation to the supporting elements respectively. Fig. 5 is an enlarged fragmentary view of one of the anchor members. Fig. 6 is a perspective view of two mold walls assembled in knock-down position for shipment. Fig. 7 is a perspective view of a mold, including the mold walls and a set of units similar to those shown in Fig. 1 to 4 respectively, assembled in position to receive the concrete. Fig. 8 is a fragmentary view, partly in section, showing one of the anchors as it appears when embedded in the concrete of a stable floor or beam. 90

Like parts are identified by the same reference characters throughout the several views.

The anchorage members illustrated in the drawings are similar to those shown and described in my former patent, dated July 28, 1914, and numbered 1104805. In the present application, the anchor A, (shown in Figs. 1 and 2), is a post anchor, and the anchor B, (shown in Figs. 3 and 4), is a stanchion anchor. Each of these anchors 105 110

comprises a face plate having elbowed legs, and the face plate is provided with key hole slots C adjacent to the legs, which slots are adapted to receive the heads of bolts D, substantially as shown and described in my former patent. These elements therefore require no further description. They are prepared at a shop or factory and are there assembled in connection with the mold walls 10 E and E', shown in Fig. 6. The walls E and E' constitute the side walls of a mold and are composed of ordinary planks. The anchor members A and B are supported from the upper margins of these mold walls 15 or planks by supporting spacing elements F, each of which comprises a wooden bar having a central bolt hole f to receive one of the bolts D. Each bar is also provided on each side of the central bolt hole with a 20 pair of bolt holes F', properly spaced at a distance from each other and equal to the distance between the bolts D when adjusted with their heads in the key hole slots C. This allows the spacing bars F to be assembled in superposed positions parallel with 25 the face plate of the anchor, as shown in Figs. 1 and 3, said bars being rigidly secured to said anchor face plate by the bolts D passing through the holes F', whereby 30 the bars are rigidly secured in a position extending longitudinally along the face plate. The central hole f allows each of the bars to be adjusted in a transverse position and secured to the face plate by one of the 35 bolts D, as shown in Figs. 2 and 4. When the bars are in this position, the anchor members may be assembled in proper relation to the walls E and E' of the mold, said walls being set up in accordance with a previously 40 prepared plan of the floor and floor beams of a stable to be erected. The mold members E and E' having been properly placed in accordance with such plan, the anchor units are adjusted between them in the 45 positions indicated on the plan, whereupon the mold members and the spacing bars or setting up devices are suitably marked to indicate the positions which they then occupy in relation to each other. Various means 50 may be devised for so marking the spacing elements and mold walls. I preferably provide the bars and mold walls with small holes G to receive nails or screws, whereby the bars may be rigidly connected with the 55 walls of the mold and the anchors rigidly supported from such walls. These holes may be conveniently formed by driving nails partially in place to connect the bars with the mold walls for the purpose of the factory assembly, the nails being subsequently 60 withdrawn to permit the knock-down assembly illustrated in Figs. 1, 2 and 6. If desired, however, the mold walls may be additionally marked by cross lines H to indicate 65 the positions of the spacing bars or

elements thereon. After the various elements have been separated and adjusted in knock-down form and shipped to the place of use, they may be reassembled by inexperienced workers in the position illustrated in Fig. 7, preparatory to receiving the concrete. In this position the various elements will be readjusted in exactly the same positions in which they were adjusted and marked when initially assembled at the factory. The nail holes G will accurately indicate the exact position which the bars occupy upon the mold walls and will also indicate the exact degree of separation of such walls. When reassembled at the place of use, the mold may be filled with plastic or freshly mixed concrete to the level of the under surface of the spacing bars or elements F, whereupon the upper surfaces of the anchor members A and B will be flush 85 with the surface of the concrete filling. After the concrete has set, the spacing bars will of course be unbolted from the anchors and withdrawn from the mold walls, and the mold walls may then be removed, leaving the concrete floor member or beam with the anchors embedded therein. The bolts D are removable, but if desired these same bolts may then be employed to secure posts, stanchions, etc., to the floor. 95

It will be understood that the object of the bolt holes F' in the spacing bars F is to provide means for rigidly securing said bars to the anchor members for shipping purposes, so that they will not be broken 100 while *en route* to their destination, and owing to the fact that the key hole slots C are located adjacent to the corners of the anchor members, it is obvious that the position of the holes F' will be varied to correspond with the distance between the bolts D or key hole slots C. Therefore the spacing bars, which are used in connection with the anchor members B, will have the holes F' spaced at a greater distance from each other 110 than the holes in those bars which are intended for use in connection with the anchor members A. But on the other hand, the holes G or other marking devices employed to locate the points of connection between 115 the bars F and the side walls E, E' of the mold, will be spaced at equal distances apart regardless of the length of the anchor members to which the bars pertain. In the knock-down position of the units illustrated 120 in Figs. 1 and 2, I preferably employ a strip of thin sheet metal having holes to receive the bolts D and superpose this strip J upon the bars F in order that blows or lateral strains applied to the bolts D, while the 125 devices are in transit, will not split the bars F. These strips of sheet metal J also serve as spacers to hold the bolts at the outer ends of the key hole slots when the units are re-assembled in relation to the walls of the 130

5 mold, preparatory to receiving the concrete. In this position, the spacing members not only hold the bolts at the outer ends of the slots, but also keep them in an upright position and in exactly the position which they must occupy for connection with previously prepared bases of the posts and stanchion members to be subsequently secured thereto, it being understood that substantially absolute accuracy in the position of the bolts with reference to the anchors, as well as in 10 the position of the anchors themselves, is required in order to facilitate the proper connection of the bases, etc., in accordance 15 with the plan of the building and in true alinement with each other.

I attach great importance to the use of the spacing bars F in connection with the spacing strips J in that it affords means for insuring absolute conformity to the plan. The fact that in a modern stable the various posts, frame members and also the mangers are formed of metal, makes it peculiarly essential that the connecting members be 25 accurately located, no facilities existing at the ordinary farm for boring new holes or enlarging or elongating holes in a metallic structure to suit the requirements of imperfect adjustments or alinement.

30 In Fig. 7 no end walls are illustrated for the mold shown in said figure. In many instances the walls of the building constitute the end walls of the mold. Where other end walls are required, they can of course be 35 supplied at the place where the building is erected. It will also be observed that in the drawings the anchor members are illustrated as supported from a plurality of mold walls. Wherever this can be conveniently done, it 40 is desirable, since accuracy is more easily secured than in cases where the spacing members are connected with only one mold wall, but I do not limit the scope of my invention to any specific number of mold 45 walls, nor to any specific form of the spacing elements.

I claim—

50 1. Means for positioning an anchor, comprising a set of spacing members having means to engage the anchor in positions parallel to it and also, when adjusted, transversely thereto, the end portions of said spacing members provided with means for determining the points of attachment to the 55 walls of a mold.

2. Means for positioning an anchor having a face plate provided with bolt-receiving

slots, said means comprising a pair of spacing bars having apertures substantially centrally of their ends and bolts in said apertures engaging the face plate slots when the spacing bars are disposed transversely of the face plate, said spacing bars also having apertures spaced a distance corresponding to the distance between the face plate slots 60 to receive said bolts when the spacing bars are disposed in alinement with the face plate and in superposed relation.

3. Means for positioning an anchor having a face-plate provided with key-holes, 70 said anchor positioning means comprising a pair of spacing bars each provided with apertures spaced a distance corresponding to the distance between the key holes of the anchor face-plate, said key holes and apertures receiving securing means for fastening the bars in superposed relation in alinement with the anchor face plate, said spacing bars also each having an aperture to aline 75 with the key holes in the face plate when the spacing bars are disposed transversely to said plate whereby the bars may be secured to the face plate in said transverse position.

4. Means for positioning an anchor having a face-plate, comprising anchor positioning members adapted to be detachably secured to said face-plate in superposed relation and in alinement with said plate, said members also adapted to be detachably secured to the face plate in transverse alinement thereto whereby the anchor may be positioned between the walls of a mold. 85

5. Means for positioning an anchor having a face-plate provided with slots, comprising positioning members having apertures to aline with said slots when the members are disposed transversely to the face-plate to receive bolts for securing said members in said transverse position, said members 90 also provided with apertures to aline with the slots when the members are disposed in alinement with the face-plate and superposed thereon to receive said bolts for securing the members in said superposed 95 alined position, and a spacing member receiving the bolts and holding the members 100 in their spaced transverse position.

In testimony whereof I affix my signature in the presence of two witnesses.

JOHN JAMES.
